UNITED STATES PATENT OFFICE.

TAMIS CORNELIS SCHENK, OF AMSTERDAM, NETHERLANDS.

CLAMP FOR ANGULAR AND CROSS CONNECTIONS OF BEAMS.

1,382,249.

Specification of Letters Patent. Patented June 21, 1921.

Application filed April 30, 1920. Serial No. 377,898.

To all whom it may concern:

Be it known that I, TAMIS CORNELIS SCHENK, diamond-worker, a subject of the Queen of the Netherlands, residing at Amsterdam, Van Woustraat 93, the Netherlands, have invented certain new and useful Improvements in Clamps for Angular and Cross Connections of Beams, of which the following is a specification.

- 10 The invention relates to a clamp, by means of which angular and cross connections of beams, or in general of pieces of wood of a certain thickness, can be readily and firmly effected, and which can be used repeatedly.
- 15 The clamp consists of a lever, one end of which is bent at right angles, while the other end or leg is bent at an obtuse angle transverse to the plane of the square end and is bent to form a hook at that end, and of a 20 locking piece, closely fitting the inner side of the bent end of the said leg when the clamp takes the working position.

The square bent end as well as the locking piece may be provided with teeth at the inner side for forming a more effective gripping surface. In using the clamp for angular connections of beams the lever is preferably shaped as a T-piece, the square bent end then being the cross-piece of the T, 30 whereas the other leg is bent through an obtuse angle.

Two applications of the invention are illustrated in the accompanying drawing, the objects to be clamped being in the first 35 case two beams, joining each other at right angles, in the second case two beams placed crosswise.

Figure 1 is a front elevation of the clamp for an angular connection of beams.

- 40 Fig. 2 is a side elevation thereof, while Fig. 3 is a plan view.

Fig. 4 shows two beams, joining each other at right angles and kept together by the clamp.

45 Fig. 5 is a section taken diagonally through the beams at their point of intersection, the clamp taking the closed position.

Fig. 6 is a corresponding section, the clamp being opened.

50 Fig. 7 is an inner view of the clamp for a cross-connection of beams.

Fig. 8 is a side elevation.

Fig. 9 is a plan view of Fig. 8.

55 Fig. 10 shows the clamp in clamping position in use with two cross beams.

The clamp according to Figs. 1-6 consists

of a T-piece, the crosspiece of which is designated by 1 and the other leg by 2. The leg 2 is bent through an obtuse angle transverse to the plane of the T-piece and the bent end 3 terminates in a hook 4.

The crosspiece fits against the leg 2 and is at the inner side provided with teeth 5. A loose locking piece 6, having substantially the same shape as the crosspiece 1, can be placed against the bent end 3. The locking piece has an aperture 7 in the center, into which, after being placed in the hook 4, the hook end can be bent inside, so that the locking piece is held with some clearance. The locking piece as well as the crosspiece has teeth 5 at the inner side.

When the clamp is initially placed in position as shown in Fig. 6, then the locking piece 6 makes an acute angle with the bent end 3 of the leg 2 and the points 8 and 9 lie approximately opposite each other.

The bellcrank lever, formed by the locking piece and the T-piece, can then be moved through the collapsing point into the position according to Fig. 5 by tilting over the locking piece, for instance by means of a screw-wrench or the like, or by pressing against the leg 2 of the T-piece.

The clamp according to Figs. 7-10 consists of a lever 10, bent at right angles at one end to form a hook 11, having a flat gripping surface 12, the other end 13 of the lever being bent through an obtuse angle in a direction transverse to the plane of the hook 11. The bent end 13 terminates in a hook 14. The locking piece is now otherwise shaped and consists of a plate 15 with gripping-surface or foot 16 and an aperture 17 for the hook 14. A lug 18 arranged perpendicular to the bent end 13 of lever 10 at the inner side, fits, when the clamp is closed, with the inner side against the locking piece. The locking piece can be placed in the clamping position by means of a wrench or the like. The working of this clamp is for the rest the same as of the clamp according to Figs. 1-6.

What I claim and desire to secure by Letters Patent is:

1. A clamp for members disposed at angles to each other comprising a body; a jaw at one end of the body and rigidly connected therewith, said jaw having a clamping surface for engagement with the material to be clamped; a coacting jaw fulcrumed at the other end of the body and

also having a clamping surface to engage the material to be clamped, said fulcrumed jaw and body forming a toggle pivoting on the two jaws whereby a clamping action is produced when the toggle is closed and the material is confined between the jaws, the body and jaws being so shaped that the body which comprises a single relatively narrow rod fits into the corner produced by the two angularly disposed members to be clamped and in close proximity to the two members, while the jaws are in position to engage the members and clamp them together when the toggle is closed.

10 15 2. A toggle clamp for members disposed at angles to each other comprising a body in the form of a single rod; a fixed jaw at one end thereof; another jaw fulcrumed substantially midway its length at the other end of the body, said body and fulcrumed jaw constituting a toggle to clamp the members together when the toggle is closed; and a hook and eye connection between the body and the fulcrumed jaw whereby the former and latter are maintained in mechanical connection with each other with the fulcrumed jaw engaging the body midway its length. 20 25

In testimony whereof I affix my signature.

TAMIS CORNELIS SCHENK.
